UNITED STATES PATENT OFFICE.

HOWARD D. COLMAN, OF ROCKFORD, ILLINOIS, ASSIGNOR, BY MESNE ASSIGNMENTS,
TO EDGAR S. NETHERCUT, OF EVANSTON, ILLINOIS.

WINDER.

Application filed January 4, 1917, Serial No. 140,561. Renewed May 21, 1926.

This invention relates to machines for winding thread, yarn, twine or the like, and refers particularly to the rewinding of yarn or the like from a plurality of relatively small 5 yarn masses to form a larger yarn mass. The invention is applicable to the rewinding of successive bobbins or other supply yarn masses to form a relatively large 10 yarn mass or cop containing a single thread; to machines for simultaneously rewinding a plurality of supply yarn masses to form a section beam or other relatively large yarn mass containing a plurality of warp threads; to doubling machines wherein a plurality of 15 threads are wound parallel preparatory to twisting; and to various other types of winders.

The prime object of the invention is to produce an organization of parts which will 20 permit uninterrupted winding at relatively high speed.

Among the subsidiary objects of the invention are to provide a magazine and mechanism for automatically bringing successive 25 supply yarn masses into operative position; to provide simple and effective means for placing the running thread and a reserve thread in operative relation to a knotter; to provide means for actuating the knotter to 30 tie the knot with the swiftness required by the high rate of speed at which the machine is intended to operate; to provide means whereby the knotter may tie the knot before the end of the exhausted thread can pass the 35 knotter; and to provide means whereby the winding of the receiving yarn mass may continue while the thread is clamped during the tying of the knot.

In the accompanying drawings, Figure 1 40 is a front elevation of a winder embodying the features of my invention. Figs. 2 and 3 are sectional views of a detector-controlled circuit-closer. Fig. 4 is a fragmental plan view of the winder. Fig. 5 is a horizontal 45 sectional view showing the reserve-thread hook and one of the stop pins for holding the reserve thread out of contact with the tension-reducing means. Fig. 6 is a vertical sectional view taken approximately in the plane of dotted line 6 of Fig. 5. Fig. 7 is a front elevation of the parts shown in Fig. 5. Fig. 8 is a fragmental elevation looking from the left-hand side of Fig. 1. Fig. 9 is a perspective view of a certain thread support. 50 Fig. 10 is a view of a circuit-closer. Fig. 11

is a view of a certain device comprised in the resetting means. Fig. 12 is a side view looking from the right-hand side of Fig. 1. Figs. 12^a and 12^b are views of a portion of the means for indexing the bobbin magazine, 60 Fig. 12^b being a view taken in the horizontal plane indicated by the dotted line 7 in Fig. 12^a. Fig. 13 is a fragmental rear side view of the machine. Fig. 14 is a fragmental elevation illustrating the knot-tying mechanism. 65 Fig. 15 is a fragmental detail illustrating the means for resetting the knotter-actuating shaft. Fig. 16 is a detail view of a certain thread-guiding plate. Fig. 17 is a view of certain of the parts shown in Fig. 14. Fig. 18 is a view of a thread clamp comprised in the knot-tying mechanism. Fig. 19 is a sectional view of the thread clamp taken in the plane of dotted line 19 of Fig. 18. Fig. 20 is a fragmental vertical sectional view, looking forward. Figs. 21 and 22 are sectional 70 views of an air valve. Fig. 23 is a fragmental vertical sectional view showing the magazine, the detector and the tension-reducing means. Fig. 24 is a sectional view of one 80 of the reserve-thread clamps. Fig. 25 illustrates a means for turning the detector shaft, the view being taken in the plane of dotted line 25 of Fig. 26. Fig. 26 is a vertical view of said turning means. Fig. 27 is 85 a horizontal sectional view of the detector showing the parts in the normal or running position. Fig. 28 illustrates the position assumed by the detector when the thread exhausts. Fig. 29 is a view showing the position assumed by the detector just prior to the insertion of a new thread into the detector. Fig. 30 is a horizontal sectional view through one of the skewers for supporting the bobbins. Fig. 31 is a horizontal sectional view 90 showing the magazine, certain thread guides and the yarn clearer. Fig. 32 is a horizontal sectional view showing the means for turning the magazine and for opening and closing the yarn clearer. Fig. 33 is a fragmental 100 horizontal sectional view through the magazine. Fig. 34 is a sectional view of the yarn clearer. Fig. 35 illustrates a pawl and ratchet included in the magazine-turning means. Fig. 36 is a horizontal sectional view 105 taken in the plane of the main shaft. Fig. 37 is a fragmental detail of the tension-reducing means. Fig. 38 illustrates a certain thread-controlling stop. Fig. 39 is a view taken in the plane of dotted line 39—39 of Fig. 41, 110

and illustrating a belt shifter. Fig. 40 is a fragmental detail view of the means for locking the belt shifter. Fig. 41 illustrates a brake to stop the main shaft. Fig. 42 is a fragmental vertical sectional view of the tension-reducing means. Fig. 43 is a view of a portion of the periphery of the tension-reducing means.

The illustrative embodiment herein shown 10 of the invention comprises means for rewinding the yarn of successive bobbins *a* to form a yarn mass *b*. The running thread is indicated in the various views at *x*. The yarn mass *b* is herein shown as consisting 15 of yarn spirally wound upon a tubular flangeless core *c*, but, as hereinbefore stated, the invention is not limited to the production of yarn masses of any particular character or size. The supply yarn masses also 20 may be of various types and may be supported in various ways. I have herein shown ordinary warp bobbins with yarn wound thereon with the so-called "warp-wind", wherein the yarn is wound upon 25 the bobbin in concentric cylindrical layers, as distinguished from the "filling wind", wherein the yarn is wound upon the bobbin in successive conical layers. In the machine 30 herein illustrated, the bobbins are supported for the drawing of the yarn off the ends of the bobbins, as warp-wound yarn may be successfully drawn off the ends of the bobbins at greater speed than filling-wound 35 yarn.

35 The bobbins *a* are supported in a magazine 1 which may be of any suitable construction, that herein shown comprising a disk 2 (Figs. 1 and 23) having a hub 3 which is fixed upon a vertical spindle 4. Said spindle is rotatably mounted in bearings 5, 6 and 7, in the supporting framework. Means hereinafter described is provided for rotating the magazine step by step as required to move a spent bobbin out of running 40 position and place a reserve bobbin in running position. The magazine is arranged to contain eight bobbins, each of which is supported in vertical position upon a skewer 8. As indicated in Fig. 30, the skewer 8 consists of a plurality of longitudinal sections 9 movable radially in and out to clamp and release the bobbin. A contractile ring 10 (Fig. 23) encircling the lower portions of the segments 9 tends to draw the 45 segments together. The skewer has an annular shoulder 11 upon which the butt of the bobbin may stand. Above the shoulder 11 the skewer is provided with two annular surfaces 12 and 13 adapted to engage the 50 walls of the bore of the bobbin when the skewer is expanded, the surfaces 12 and 13 being spaced apart, as indicated in Fig. 23, in order that the bobbin shall be gripped at two separated places and thus be firmly and 55 concentrically held at each of those places.

The means for expanding the skewer comprises a pin 14 mounted in a tubular guide 15 carried by the plate 2. The upper end of the guide 15 is upwardly tapered as at 16, and fits within the correspondingly tapered 60 lower end of the skewer. The upper end of the pin 14 has a downwardly tapering surface 17 adapted, when the pin 14 is moved downwardly, to force the upper ends of the segments 9 apart and thus cause the skewer 65 to engage the bobbin. A coiled expansion spring 18 surrounds the pin 14 within the guide 15 and bears against an annular shoulder 19 on the pin. It will be seen that the spring 18 tends to cause the tapered surface 17 to enter between the upper ends of the segments 9 and also tends to move the skewer bodily downward over the tapered surface 16, the result being to expand the 70 skewer into clamping engagement with the interior walls of the bobbin. Inasmuch as the skewer comprises the clamping portions 12 and 13 which are movable by the conical surfaces 16 and 17 until they come into contact with the interior walls of the bobbin, 75 the skewer is capable of firmly clamping bobbins having bores of various sizes and tapers.

The skewers are caused to clamp and release the bobbins in the rotation of the magazine by means of a cam flange 20 (Figs. 23 and 32) on the bracket that supports the bearings 6 and 7. The low portion of the flange 20 is indicated at 21 in said figures, the portion 21 being joined to the elevated portion of the flange by the inclines 22 and 23. In the rotation of the magazine the pins 14 are moved around on the flange 20. When the pins are on the elevated portion of the flange, the skewer is in the contracted 80 condition shown at the right-hand side of Fig. 23. When the pins 14 are above the low portion 21, the skewers are in the expanded or clamping condition shown at the left-hand side of Fig. 23. (The bobbin-supporting, clamping and releasing means is claimed in my divisional application Serial No. 149,346, filed Nov. 19, 1926.)

The magazine 1 further comprises partitions 24 forming individual compartments 115 for the bobbins. The outer sides of these compartments are open for the removal of empty bobbins and the insertion of full bobbins. At one side of the magazine is a segmental wall 25 (Figs. 23 and 31) which 120 serves to close the compartment of the running bobbin and the compartment of the bobbin next to be unwound.

The free ends of the threads on the bobbins *a* may be supported in any suitable manner. Herein they are shown as held by individual clamps 26 (Fig. 24) arranged in a circular series above the respective compartments of the magazine. As shown in Fig. 23, a disk 27 is fixed to the spindle 4, 125

said disk having a peripheral upwardly-extending flange 28. Pivoted to the flange 28 at 29 are the arms 30, each arm being adapted to clamp a thread against the flange 28. The free end 31 of the arm 30 is bent outwardly to form with the flange 28 a flaring throatway or guide 32 to receive the thread. A stud 33 fixed to the arm 30 projects freely through an opening in the flange 28. Between the flange 28 and a washer on the stud 33 is an expansion spring 34 that normally holds the arm 30 against the flange 28 to clamp the thread. A lug 35 on the arm 30 extends under the disk 27 and limits the extent to which the thread may be inserted between the arm 30 and the flange 28. The means for successively opening the clamps 26 to release the threads held therein comprises, in this embodiment of the invention, a flange 36 on a part fixed to the framework of the machine, said flange lying within the path of movement of the studs 33 and having an inclined or cam portion 37 (Figs. 4 and 24) for forcing the arm 30 away from the flange 28 to release the thread. After being thus opened, the clamp is held open by the flange 36 until the stud 33 reaches the cam portion 37^a (Fig. 4) when the spring 34 is allowed to close the clamp in readiness to receive the thread of a new bobbin.

Means is provided to form a guide for the thread at a point in alinement with the axis of the bobbin. This means includes a flange 39 (Figs. 23 and 31) upon the upper end of the curved wall 25. The edge 40 of said flange is curved upon the arc of a circle concentric with the magazine 1. The edge 41 of the flange serves to guide the threads of successive bobbins onto the edge 40. To cooperate with the edge 40 in guiding the thread there is provided for each compartment of the magazine a thread guide 42 having a notch 43 to receive the thread and inclined edges 44 to guide the thread to said notch. Each thread guide 42 is fixed to the upper end of an arm 45, said arm being pivoted intermediate its ends at 46 to a support 47 fixed to the spindle 4. The lower ends of the levers 45 lie within a cam groove 48 of a stationary disk 49. As the magazine is rotated, the levers 45 are swung to move the thread guides 42 into and out of operative position. As shown in Figs. 23 and 32, the cam groove 48 is of such form as to move the thread guides 42 into operative relation with the edge 40 of the flange 39 as the compartments of the magazine approach the running position. Upon the upper end of each lever 45 is a projection 50 (Figs. 23 and 31) that lies within a groove 51 formed in the lower side of a disk 52 fixed to the spindle 4. The projection 50 and the groove 51 prevent lateral movement of the levers 45 and thread guides 42. The projection 50

also serves by engagement with the outer end wall 53 of the groove 51 to limit the outward movement of the thread guide 42, the notch 43 being thus accurately located in axial alinement with the bobbin.

The means for rotating the magazine 1 step by step comprises an arm 54 (Figs. 8 and 35) rotatably mounted upon the spindle 4 between the bearings 6 and 7. Said arm carries a pawl 55 arranged to engage a ratchet wheel 56 fixed to the hub 3 of the disk 2. A torsion spring 57 (Fig. 8) holds the dog in engagement with the ratchet wheel. Rigid with the arm 54 is an arm 58 which is connected by means of a link 59 with an arm 60 which is loosely mounted upon a constantly-rocking shaft 61. The means for connecting the arm 60 to the shaft 61 when the magazine is to be turned comprises an arm 62 (Figs. 8 and 13) which is rigid with the arm 60. On the arm 62 is pivoted a dog 63 adapted to engage a shoulder 64 (Fig. 11) on a segment 65 fixed to the shaft 61. On the segment 65 is a shoulder 66 arranged to engage one side of the arm 62 to move said arm into the position shown in Fig. 8. It will be seen that the shoulder 64 when engaged by the dog 63 moves the arm 62 in the direction to turn the magazine 1, and that the shoulder 66 moves the arm 62 in the opposite direction. A spring 63^a connected at one end to the arm 62 and at its other end to a finger 63^b which is rigid with the dog 63 tends to throw the dog into the path of oscillation of the shoulder 64. The means for holding the dog up out of the path of said shoulder until the running thread exhausts, will be herein-after described. The shaft 61 is rocked by means including a crank arm 67 (Figs. 12 and 13) fixed on said shaft and connected by means of a link 68 to a crank disk 69 fixed on a shaft 70. The shaft 70 is driven from a shaft 71 through intermeshing gears 72 and 73. The shaft 71 is driven from a shaft 74 by means of a belt 75 running over pulleys 76 and 77. The shaft 74 is driven from a shaft 78 through a belt 79 running over sheaves 80 and 81 (Fig. 1). The shaft 78 is driven in any suitable way, as, for example, from a counter-shaft (not shown) by means of a belt 82 (Fig. 36), which belt is arranged to run over a tight pulley 83 and a loose pulley 84 on the shaft 78.

At the end of each movement, the magazine is held stationary by reason of the friction between the pins 14 and the flange 20. The arms 60 and 62 are frictionally held in the position to which they are returned by the shoulder 66 by means of a clamp comprising two clamp members 85 (Fig. 13) arranged to lie at opposite sides of the arm 62 and carried by a stationary bracket 86. To one of the clamp members 85 is fixed a pin 87 which extends loosely through the

other clamp member and through the bracket. An expansion spring 88 interposed between said other clamp member and a washer on the pin 87 presses the clamp members against the arm. The clamp members are preferably covered with leather or other suitable friction material.

After passing through the thread-guiding notch 43, the running thread extends through 10 a yarn clearer comprising two stationary blades 89 and 90 (Figs. 31 and 34) and a notched blade 91 adapted to enter the space between the blades 89 and 90. The lower blade 89 has a sharpened edge close to which 15 the thread runs, said edge and the cooperating blade 91 serving to clear the yarn of foreign matter and to break a thread having a gout therein. The blade 91 is fixed upon a shaft 92. The normal position of 20 the blade 91 is determined by contact of a stop screw 93 carried by said blade with a fixed stop 94. To the lower end of the shaft 92 is fixed an arm 95 (Fig. 32) to which is connected a tension spring 96 that 25 tends to turn the shaft 92 to move the blade 91 away from the blades 89 and 90. 95^a (Fig. 32) is a stop to limit the opening movement of the yarn clearer blade 91. Also fixed to the lower end of the shaft 92 is 30 an arm 97 which is arranged to be engaged by an arm 98 that is rigid with the arm 58. When the arm 58 is moved in the direction to turn the magazine 1, the arm 98 is swung away from the arm 97, thus permitting 35 the spring 96 to open the yarn clearer. When the arm 58 is returned to normal position, the arm 98 engages the arm 97 and thus closes the yarn clearer upon the new thread. The mechanism is 40 arranged to press the stop 93 firmly against the stop 94 and thus hold the blade 91 stationary in proper position.

After leaving the yarn clearer, the running thread extends through a detector 99 45 to be hereinafter described, and thence into contact with a mechanism for reducing the tension of that portion of the thread extending from a point relatively close to the detector 99 to and beyond the knotter. This 50 mechanism is provided in order that the tension of the thread shall be greatest in the region between the bobbin and the tension-reducing means and thus insure that breakages shall not occur in the region beyond 55 the tension-reducing means. It also is desirable to keep the tension of the thread as low as possible in order that it may be wound upon the yarn carrier *c* with the least practicable degree of tension. The tension-reducing means neutralizes the tension 60 caused by the contact of the thread with the various parts against which it runs. The tension-reducing means comprises a driven roll having a surface speed which is greater 65 than the speed of winding of the thread.

Inasmuch as the bobbin that occupies the reserve position indicated in Fig. 31 is tied to the exhausted thread and commences unwinding a few moments before it is transferred to the running position, I preferably 70 provide two tension-reducing means, one for the thread while it is being unwound from a bobbin in the reserve position, and the other for the thread after its bobbin has been placed in the running position. 75 Both of these tension-reducing means are identical in construction and are indicated at 100 and 101 in Fig. 36. Each consists of a wheel 102 fixed upon the shaft 78 and carrying a peripheral series of staggered pins 103. The pins are staggered as shown in Fig. 43 in order to cause the thread to bend as it passes from one pin to the next, thus producing a considerable arc of contact between the thread and the pins and thereby providing a sufficient amount of friction between the pins and thread. Alternate pins are inclined in opposite directions as indicated in Figs. 36 and 43, so that the pins provide in effect a groove, V- 90 shape in cross-section, upon the periphery of the wheel 102 to receive the thread. The thread does not run in contact with the periphery of the wheel 102. When there is a momentary increase in the tension of the thread between the bobbin and the tension-reducing means, the thread is drawn farther down between the pins 103, whereby the arc of contact of the thread with the pins is increased, thus increasing the effectiveness of the tension-reducing means. When the tension of the thread between the bobbin and the tension-reducing means decreases, the thread moves farther out on the pins, thereby reducing the effectiveness 95 of the tension-reducing means. The latter thus equalizes the tension of the thread in the region beyond the tension-reducing means. 100

At each side of the series of pins 103 is a ring 104 fixed to the wheel 102. The adjacent portions of the rings 104 overhang the points of the pins 103 to prevent the thread from fouling on the pins, and the adjacent surfaces of said overhanging portions are inclined so as to permit the thread to move easily into and out of engagement with the pins. The two middle rings 104 are united by a cylinder 105. It will be seen that the rings 104 and cylinder 105 constitute in effect a roll having near each end a V-shape groove to allow the thread to pass into contact with the pins 103. The ring 104 at the side from which the reserve thread approaches is partially overhung by an annular flange 106 fixed in the framework of the machine, said flange preventing the thread from passing down beside the end of the roll. 115

The knotter may be of any suitable type. 120 125 130

Herein I have shown a knotter comprising a tying bill 107 (Figs. 14 and 17) substantially similar to the one shown in my application Serial No. 83,008, filed March 9, 1916 5 (Patent No. 1,450,941, dated April 10, 1923). The movable shearing and clamping jaw of the tying bill is swung with relation to the stationary jaws of the tying bill by means of a cam barrel 108 like the one disclosed in 10 said application. The shaft of the tying bill has a pinion 109 fixed thereon similar to the one shown in said application, which pinion meshes with a gear segment 110 similar to the segment illustrated in said application. The segment 110 is fixed upon a shaft 111 that is mounted in bearings 112 and 113 (Figs. 4 and 17). The tying bill 107 normally stands in the position shown 15 in Figs. 4 and 14 and the active thread runs within the angle formed between the tying bill and its shaft, as indicated in Figs. 4, 14 and 17. At the side of the tying bill from which the thread approaches is a stationary plate 114 (Figs. 14 and 20) having a thread-guiding notch 115 therein. Directly behind 20 said plate is an exhaust air tube 116, the mouth of which has a notch similar to the notch 115, said notches being in register with each other. The tube 116 is connected with a suitable air-current-creating means (not herein shown). Between the tube 116 and the tying bill 107 is a stationary plate 25 117 (Figs. 14 and 17), said plate having a notch 118 therein. The running thread extends through the lower portion of said notch, as indicated in Fig. 17. The reserve thread normally stands in the upper portion of the notch 118 as shown in Fig. 17.

A spring finger 119 bears against the 40 forward side of the plate 117 and is arranged to push the reserve thread from its normal position and into place alongside the exhausted thread in order that the tying bill may loop the two threads together. The 45 finger 119 is fixed upon a rock shaft 120. Also fixed to said shaft is a crank disk 121 (Fig. 20) carrying a crank pin 122 that lies in the slot of a cam 123, which cam is fixed upon the shaft 111. By reference to Fig. 50 20, it will be seen that the shaft 120 is rocked to place the reserve thread beside the exhausted thread and clamp both threads at the lower end of the slot 118 at the beginning of the knotter-actuating movement of the shaft 111. The finger 119 is made broad as shown in Fig. 17, so that when the waste ends are exposed to the suction current, said ends shall not foul on the finger 119.

Rearwardly of the tying bill is a means 60 for clamping the exhausted thread and the reserve thread, which means comprises a clamping member 124 (Figs. 18 and 19) fixed upon the rock shaft 120, and two stationary spring clamping jaws 125 between which the threads are forced by the clamp-

ing member 124. The clamping member 124 is arranged to swing between two stationary plates 126 and 127, each having a thread-guiding slot 128 therein.

Between the plate 127 and the tying bill 70 is a stationary plate 129 (Figs. 14 and 16) having a thread-receiving slot or notch 130. The slots 128 and 130 are of the same size and shape and register with each other. As indicated in Fig. 17, the slot 118 is not so deep as the slots 128 and 130. Thus the clamp finger 119 acts to clamp the threads early in the cycle of the tying operation, and thereby enables the winding to take out the slack in the exhausted thread (caused by 80 the jumping of said thread when it exhausted) before the tying bill engages the threads to form the loops.

The means for pulling the loops of the knot off of the tying bill, for drawing the loops 85 tight and for pulling the ends of the united threads out of the tying bill comprises a stripper arm 131 fixed upon the shaft 111 and having a forked end to engage the united threads. The stripper arm 131 is arranged to swing through the space between the plates 127 and 129, as shown in Figs. 14 and 19.

The means for actuating the knotter to tie the knot with great rapidity comprises a 95 torsion spring 132 surrounding the shaft 111, one end of said spring being secured to the framework of the machine and the other end of the spring bearing against a pin 133 (Fig. 20) upon an arm 134 fixed on the 100 shaft 111. The knotter is normally held in the initial or thread-receiving position by means including a collar 135 (Fig. 17) having a shoulder 136 that supports the arm 134 against the torsion of the spring 132. 105 The collar 135 is fixed upon a shaft 137 (Figs. 4 and 14) which is supported at one end in an arm 138 (Figs. 14 and 20) pivoted at 139 in the framework of the machine to swing toward and away from the shaft 111. 110 On the lower end of the arm 138 is a projection 140 which is normally held against a stationary stop portion 141 by an expansion spring 142. The end of the shaft 137 that carries the collar 135 is supported in 115 the yieldingly mounted arm 138 in order that the collar 135 may be forced aside by the arm 134 as said arm is being reset to normal position. As soon as the arm 134 has passed the shoulder 136, the spring 142 120 forces the shoulder 136 beneath the arm 134 to retain the arm 134 in initial position. The shaft 137 is normally held in the position shown in Fig. 17 by means of the detector, as will appear hereinafter.

When the bobbin is being carried by the magazine into the reserve position shown in Figs. 5 and 31, the thread extending upwardly from said bobbin moves into a throatway 143 (Figs. 4 and 5) formed by 130

two stationary plates 144 and 145, the inner end of which throatway is adjacent to and is directed toward the tension-reducing means 100. The reserve thread stops against 5 two pins 146 and 147 (Figs. 5, 6 and 7), which pins are supported for simultaneous movement into and out of the inner end of the throatway. For convenience in manufacture, the pins 146 and 147 may form the 10 legs of a U-shaped piece of wire, as herein shown.

The means for drawing the reserve thread into proximity to the knotter comprises a hook 148 (Figs. 4, 8 and 20), which hook is 5 pivotally mounted upon an arm 149, said arm being pivoted to the framework at 150. The arm 149 is swung by means of a link 151 extending to the arm 62. Rigid with the hook 148 is an arm 152 carrying a roller stud 153 that is adapted to enter a cam slot 154 (Fig. 8) in a stationary plate 155. A spring 156 (Fig. 20) is connected to the arms 149 and 152 so as to swing the arm 152 against a stop 157 on the arm 149. 158 is an adjustable stop carried by the arm 149, against which stop the arm 152 is forced as the roller stud 153 approaches the inner end 30 of the cam slot 154 for the purpose of holding the hook 148 against vibration when in normal position. Such vibration would tend to cause the reserve thread to become slack.

When the arm 149 swings forwardly, the hook 148 is swung upwardly into the dotted-line position indicated in Fig. 8 and is thus 35 carried over a partition or guard-plate 159, said plate extending from a point above the knotter to a point close to the tension-reducing roll and the stop pins 146 and 147. As indicated in Figs. 6 and 7, the plates 144 and 40 145 are notched to accommodate the point of the hook 148. It will be noted in Fig. 5 that the edge 160 of the hook 148 is inclined so as to push the reserve thread aside as the hook advances. As soon as the point of the 45 hook has passed the thread, the thread returns to the position shown in Fig. 5. Upon the rearward movement of the hook 148, the point of said hook catches the reserve thread between the pins 146 and 147 and 50 draws a bight or loop of the thread rearwardly, the thread to form such loop unwinding from the bobbin. The inclined edge 161 (Fig. 5) of the hook 148 crowds the strand *y* (Figs. 4 and 6) of the loop over 55 to one side. The strand *y* is drawn by the hook 148 along one side of the partition or guard plate 159, while the strand *z* is drawn by the hook 148 along the other side of the guard plate 159 and through a channel 162 (Fig. 7). Said channel is formed of the 60 guard plate 159, a bottom wall 163 and a vertical wall 164, the parts 159, 163 and 164 preferably being formed from an integral piece of sheet metal. As the hook 148 completes its rearward movement, it is swung

downwardly through the action of the inner end of the cam slot 154 (Fig. 8) upon the roller stud 153. As the hook 148 is thus swung downwardly, the strand *y* is laid upon a stationary thread support 165 (Figs. 8 70 and 20), and the strand *z* is lowered into the throatways 115 (Fig. 20), 118 (Fig. 17), 130 (Fig. 16), and 128 (Fig. 18). The strand *z* then occupies the position shown in Figs. 4, 14 and 17. The strand *y* extends to the reserve bobbin, while the strand *z* extends to the reserve thread clamp 26 and is destined to be sheared off by the tying bill and be withdrawn through the suction tube 116.

A moment before the knot is tied, the pins 80 146 and 147 are withdrawn in order that the strand *y* may drop into engagement with the tension-reducing means 100, and to provide slack in the strand *z*, which slack is later given up to the tying bill. Said pins are 85 moved by means of a lever 166 (Figs. 4 and 5) pivoted at 167. The lever 166 is connected by means of a link 168 to a crank arm 169 (Fig. 17) fixed on the shaft 120, the pins 146 and 147 being thus withdrawn at 90 the beginning of the knotter-actuating movement of the shaft 111.

It is necessary that there shall be sufficient thread between the detector and the knotter so that the end of the exhausted thread shall 95 not pass the knotter before the knotter is actuated to tie the knot. Inasmuch as the machine herein shown is designed to operate at high speed, the necessary length of thread between the detector and the knotter is obtained by looping the thread between those 100 points, the loop being clearly shown in Fig. 8. The loop is produced by means of an arm 170 pivoted in the framework of the machine and provided at its free end with a 105 plate 171 having a notch 172 (Figs. 4 and 13) in its lower edge. Rigid with the arm 170 is a gear segment 173 (Fig. 8) that meshes with a gear segment 174 which is rigid with the arms 60 and 62. When the arm 170 swings downwardly, the lower edge of the plate 171 engages the running thread and draws it down into the form of a loop as shown in Fig. 8. The plate 171 is made of considerable height and width in order that when the free end of the exhausted thread jumps said free end shall be kept away from the ascending side of the loop and thus prevented from tangling.

In order that the winding of the yarn mass *b* may continue while the thread is clamped at the knotter, I support a portion of the thread between the knotter and the yarn mass *b* in the form of a releasable loop. From the knotter the running thread extends to a thread support 175 (Figs. 4 and 8), thence at a right angle to a thread guide 176, thence past a detector 177, thence around a tension-reducing sheave 178 having 120 a peripheral speed greater than the speed 125 130

of winding, thence to a thread guide 179 (Fig. 1), thence through the notch of a thread-guiding plate 180 (Figs. 1 and 4), and thence to the winding means. When the knotter is actuated to clamp the running thread and the reserve thread, the running thread is released from the thread support 175. In the continuation of the winding the running thread is then drawn into a straight line joining the thread guide 176 and a stationary thread guiding plate 181 (Fig. 8), as indicated at x' in Fig. 4. The plate 181 has a widely-flaring notch 182 to receive the thread. The path of the thread between the points 182 and 176 is sufficiently shorter than the path defined by the points 182, 175 and 176 to allow the exhausted thread and the reserve thread to be tied together and the knot to be released from the knotter by the stripper 181 (Fig. 17) and the clamp member 124 during the continuance of the winding. The thread support 175 (Figs. 8 and 9) is formed on a plate 183 which is fixed to the link 151. When the arm 149 swings forwardly to take a new reserve thread, the plate 183 is drawn forwardly to a position alongside the thread guide 181, the inclined upper edge 184 of the plate 183 crowding the running thread up a little until the support 175 is forward of the running thread, whereupon the thread snaps down behind said support 175. The lug 175^a of the support 175 supports the thread while the support 175 is forward of the notch 182. When the arm 149 swings rearwardly with the new reserve thread, the plate 183 moves the thread rearwardly to the position shown in Figs. 4 and 8, thus reestablishing the normal path of the running thread.

The means hereinbefore referred to for disengaging the thread from the support 175 comprises a finger 185 (Figs. 4 and 13) carried by the shaft 111, the free end of which finger normally underlies the running thread directly in front of the support 175. When the knotter is actuated to clamp the running thread, the finger 185 swings upwardly, thereby knocking the running thread off the support 175. In order to prevent breakage in case the finger 185 should be actuated while the lug 175^a is moving rearwardly above said finger, the latter is preferably of spring construction in order that it may yield. Herein it is shown as held by a torsion spring 186 against a stop 187 carried by the shaft 111.

The means for resetting the knotter-actuating shaft 111 comprises a pinion 188 (Figs. 4, 13 and 15) loosely mounted on said shaft and meshing with a segment 189 carried by a lever 190 pivoted in the supporting frame. The lower end of the lever 190 carries a roller stud that lies in the groove of a cam 191, which cam is rigid with the arms 60 and 62 and the segment 174. On one side of the

pinion 188 is a lug 192 (Fig. 15) which is arranged to engage a shoulder 193 on a collar 194 (Fig. 4) fixed on the shaft 111. When the shaft 111 is released by the shoulder 136 to the action of the torsion spring 132, the shoulder 193 swings in the direction indicated by the arrow *a* in Fig. 15. When the shoulder 64 of the segment 65 (Fig. 11) engages the dog 63 and moves the arms 60 and 62, the segment 174 and the cam 191, the pinion 188 is moved in the direction indicated by the arrow *b* in Fig. 15, in which movement the lug 192 engages the shoulder 193 and moves said shoulder into the position shown in Fig. 15. When the segment 65 swings in the opposite direction, the pinion 188 is returned to the position shown in Fig. 15.

When the arm 134 is released by the shoulder 136, it is swung by the torsion spring 132 against a buffer or yielding stop 195 (Fig. 20) carried by an arm 196 fixed on a shaft 197. A torsion spring 198 (Fig. 4) surrounding the shaft 197 is secured at one end to a stationary part and bears at its other end against the arm 196, said spring normally holding the arm 196 against the stop pin 199. The spring 198 is stronger than the spring 132. When the arm 134 strikes the stop 195, said stop yields to the extent indicated by dotted lines in Fig. 20, the spring 198 immediately returning the arm 196 into contact with the stop 199. The slot of the cam 123 has a dwell portion of sufficient length to allow the shaft 111 to move through the arc indicated by the full and dotted-line positions of the stop 195 in Fig. 20, without moving the clamping finger 119 (Fig. 17) or the clamping member 124 (Fig. 18).

Upon the rear end of the shaft 197 is mounted a detent finger 200 (Fig. 8) which normally lies behind the finger 63^b and thus holds the dog 63 out of the path of oscillation of the shoulder 64 on the segment 65. The rocking movement of the shaft 197 caused by the impact of the arm 134 against the stop 195 causes the detent finger 200 to be swung away from the finger 63^b, whereupon the spring 63^a places the dog 63 in the path of movement of the shoulder 64. The detent finger 200 immediately returns into position in front of the finger 63^b, due to the action of the spring 198. In order that the finger 63^b shall be able to pass the finger 200 as the segment 65 swings upwardly, the finger 200 is pivoted on the shaft 197 and is yieldingly held by a spring 200^a (Fig. 12^a) against a stop pin 200^b on a finger 200^c fixed to the shaft 197. The spring 200^a is connected at one end to the pin 200^b and at its other end to a wire 200^d fixed to the finger 200.

There is no suction current in the tube 116 until after the knot has been tied. As shown in Fig. 21, a valve casing 201 is con-

nected into the tube 116, said casing containing a valve member 202 fixed to a spindle 203. Rigid with said spindle is a crank arm 204 (Fig. 20). A tension spring 205 is connected to a pin 206 carried by said crank arm and to a stationary point in the frame of the machine. Rigid with the crank arm 204 is an arm 207 which is arranged to stop against the portion 208 of the frame. 209 is a stop pin limiting movement of the crank arm 204 in one direction. The spring 205 tends to hold the arm 207 in contact with the stop 208 or to hold arm 204 in contact with the stop 209. Rigid with the arm 196 15 is an arm 210 which normally lies alongside the pin 206. When the arm 196 is moved through the impact of the arm 134 thereagainst, the arm 210 places the valve member 202 in open position, the spring 205 20 serving to hold the valve member 202 in such position against the tendency to rebound. In the early portion of the resetting operation, the cam 191 resets the knotter-actuating shaft 111. As said shaft approaches its 25 initial position, the cam 123, acting upon the roller stud 122, causes the clamping finger 119 to release the portion of the exhausted thread and the strand α of the reserve thread which were sheared off by the tying bill 107. At about the same moment, the reserve thread clamp 26 holding the strand α is 30 opened through the movement of the magazine 1, whereupon said portions of the exhausted and reserve thread are drawn into 35 the suction tube 116 and carried away by the exhaust current.

When the arm 149 swings forward to take a new reserve thread, a projection 211 (Figs. 8 and 20) on the arm 149 engages and moves 40 the arm 207, thereby closing the valve member 202, in which position the valve member is held by the spring 205.

The detector mechanism is located in the path of the running thread when running in 45 engagement with the tension-reducing means 101 (Fig. 36.) Said detector mechanism comprises a stationary grid consisting, in this instance, of three parallel wires 212 (Figs. 20 and 27). A wire 213 projects beyond the 50 grid wires 212 and has its free end turned forwardly (as shown in Fig. 36) to assist in guiding the running thread into proper relation with the grid. The detector further comprises two parallel fingers 214 arranged 55 to swing through the spaces between the grid wires 212, said fingers being fixed to a vertical rock shaft 215. To the forward end of the shaft 137 that serves to lock the knotter-actuating shaft 111 against the 60 action of its torsion spring 132, is fixed an arm 216 (Figs. 23 and 26) having two lugs 217 and 218 arranged to bear against flat surfaces 219 and 220, respectively, upon the detector shaft 215. As shown in Fig. 25, 65 the lugs 217 and 218 are in different vertical

planes, the flat surfaces 219 and 220 also being in different vertical planes. The lugs 217 and 218 bear against the flat surfaces 219 and 220 at one side of the axis of the shaft 215. By reason of the offsetting of the lugs 70 217 and 218, said lugs act in succession to turn the shaft 215 through the required arc.

The normal position of the detector fingers 214 is shown in Fig. 27, the fingers being held in this position by the tension of the 75 running thread and thus serving to lock the shaft 137 against rotation due to the pressure of the arm 134 against the shoulder 136. When the thread exhausts, there is nothing to restrain the arm 134, the shaft 137 being 80 turned in the downward swing of said arm 134 and the lugs 217 and 218 causing the shaft 215 to turn into the position indicated in Fig. 28. When the shaft 137 is turned by the arm 134, a pin 221 (Figs. 14 and 20) on 85 the shaft 137 swings against a pin 222 carried by an arm 223 fixed upon the forward end of a shaft 224. To the rear end of the shaft 224 is fixed a crank arm 225 (Fig. 13) which has a pin-and-slot connection with 90 the lever 190. When said lever is moved to reset the knotter-actuating shaft 111, the shaft 224 also is rocked to raise the pin 221 to a point a little above its normal position. In such returning movement of the shaft 95 137, the arm 216 presses against a pin 226 (Fig. 28) fixed to the detector shaft 215 and thus moves said shaft in the return or forward direction. After the arm has moved the shaft a distance through pressure against the pin 226, a lug 227 on the arm 216 engages a pin 228 on the detector shaft and completes the movement of the detector shaft into the position shown in Fig. 29. The detector fingers 214 are thus placed in position 100 105 to receive the running thread. 229 is a stationary stop finger lying in the path of the forward swing of the lower detector finger 214 and serving to limit such forward movement of the detector fingers.

After the arm 216 has moved the detector shaft into the position shown in Fig. 28, the shaft is free and may turn in the forward direction. If it should do so, the lugs 217 and 218 would press against the periphery 110 of the shaft in the resetting operation. In order that the shaft 137 may yield longitudinally in such event, the shaft 137 is mounted for slight longitudinal movement, being 115 yieldingly held in normal position by an expansion spring 137^a (Fig. 14) bearing against a disk 137^b that lies at one end of the shaft 137. Normally the spring 137^a does not exert any pressure against the shaft, as the plate is held against the end wall of 120 the recess containing said plate and spring, and thus prevented from bearing against the shaft.

It is desirable that the transfer of the 125 running thread from the tension-reducing 130

means 100 to the tension-reducing means 101 shall be effected in the shortest possible space of time so that the interval during which the thread is out of engagement with said 5 tension-reducing means shall be as short as possible in order that the tension of the thread in the region between the tension-reducing roll and the knotter shall be as nearly uniform as possible. I, therefore, provide 10 a stop finger 230 (Fig. 36) which for convenience is loosely pivoted upon the upper end of the shaft 92. Pivoted to said stop finger is a rod 231 (Fig. 8) that extends through a guide 232 in the frame of the machine. A collar 233 on the rod 231 is normally held against the guide 232 by a tension 15 spring 234 (Fig. 36). The free end of the finger 230 lies close to one side of the tension-reducing means 100 so as to prevent the thread from leaving said tension-reducing means. The end of the finger 230 enters an opening in a guard plate 235 (Figs. 1 and 38) which is arranged beneath the tension-reducing roll and extends from a point close 20 to said roll to a point close to the path of movement of the thread guides 42.

After the magazine 1 has been turned to bring into running position the bobbin which has just been tied to the exhausted thread, the stop finger 230 is swung forwardly to allow the thread to spring sideways (under the tension of the winding) out of engagement with the tension-reducing means 100 and into engagement with the 25 tension-reducing means 101. The stop 230 is thus moved by a cam projection 236 (Fig. 8) on the lever 170, said projection being carried in the upward swing of the lever 170 into contact with an anti-friction roller 30 on the rear end of the rod 231. Immediately thereafter the arm 170 descends, thus allowing the stop finger 230 to return to its normal position, as shown in full lines in Fig. 36. In the descent of the arm 170, the lower 35 edge of the plate 171 comes down on the strand y . The portion of said strand extending between the plate 171 and the tension-reducing means 101 is crowded over by the inclined lower edge of the plate 171 until 40 the thread runs straight from the tension-reducing means 101 to the notch 172. The manner in which the portion of the thread extending between the notches 172 and 182 reaches the running position will be referred to hereinafter.

The winding means may be of any character suited to the production of the desired form of yarn mass. In the illustrative embodiment herein shown, I have employed a 45 winding means substantially identical with that fully disclosed in application Serial No. 5,563, filed February 1, 1915 (Patent No. 1,274,386, dated August 6, 1918). The winding means comprises a drum 237 (Figs. 1 and 12) fixed upon the shaft 74. The yarn

mass b is supported in peripheral contact with the periphery of the drum 237, the thread being rapidly traversed back and forth upon the periphery of the yarn mass by means of a cam groove 238 in the periphery of the drum, as shown in said application Serial No. 5,563. The thread after leaving the thread guide 180 may, if desired, extend through a guide 239 similar to the one fully disclosed in said application Serial No. 5,563. The yarn carrier c is rotatably mounted upon an arm 241 which is pivotally supported in the framework in order that the yarn mass b may be manually withdrawn from the drum 237 when said yarn mass has reached the desired diameter, and so that another yarn carrier c may be substituted for such completed yarn mass. Any suitable means may be provided for preventing the yarn mass from becoming eccentric, as, for example, a means similar to that fully disclosed in said application.

In order to stop the machine in certain contingencies hereinafter mentioned, I provide suitable means, as, for example, a 50 brake drum 242 (Figs. 36 and 41) fixed upon the drive shaft 78, said drum being arranged to be gripped by two brake members 243 pivoted to the machine frame at 244. A tension spring 245 tends to move the brake members 243 into engagement with the drum 242. The upper ends of the brake members 243 are connected by means of links 246 to diametrically opposite points upon a crank disk 247 rotatably supported in the machine frame. Rigid with the crank disk 247 is an arm 248 which is normally held in the dotted-line position shown in Fig. 41 by a latch 249 pivoted in the machine frame. Rigid with the latch 249 is an arm carrying the armature 250 of an electromagnet 251. When the arm 248 is held by the latch 249, the brake members 243 are locked out of engagement with the drum 242. When the electromagnet 251 is energized, it attracts the armature 250, thereby releasing the arm 248, whereupon the spring 245 swings the arm 248 into the full-line position shown in Fig. 41, and draws the brake members 243 into engagement with the 100 brake drum, thereby promptly stopping the machine.

Simultaneously with the application of the brake members 243 to the drum 242, the drive belt 82 is shifted from the tight pulley 120 83 to the loose pulley 84 by means of a belt-shifter 252 (Fig. 39). An expansion spring 253 tends at all times to move the belt-shifter 252 in the direction to shift the belt to the loose pulley. The belt-shifter is normally held against such movement by means of a latch 254 (Fig. 41) pivoted in the machine frame and engaging a shoulder 255 (Fig. 40) on the belt-shifter 252. When the brake members 243 are drawn against the 130

brake drum 242 by the spring 245, one of said brake members engages an arm 256 which is rigid with the latch 254 and thus moves said latch away from the shoulder 255, thereby releasing the belt-shifter 252 to the action of the spring 253.

Simultaneously with the shifting of the belt and the application of the brake, the circuit of the electromagnet 251 is opened. I have shown an ordinary knife-switch 257 (Fig. 41) which is included in the magnet circuit, the movable contact member 257^a of which is rigid with an arm 258 that overlies the arm 254. When the arm 248 rises it lifts the arm 258 and thus opens the switch 257.

The magnet 251 is arranged to be energized if for any reason the portion of the running thread extending to the guide 176 should become slack or if there should be no thread at said guide. At 177 (Fig. 1) are located two notched thread-supporting plates 259 (Figs. 2 and 3), across which the thread runs. A pivoted detector finger 260 rests upon the thread between the plates 259. Rigid with the pivot of the detector finger 260 is a grounded contact member 261 arranged, when the detector finger drops, to swing into contact with a stationary electrical contact 262 in the circuit of the electromagnet 251, thereby stopping the machine.

It may be stated that the thread loop released by the finger 185 is drawn up so rapidly in the winding operation that the detector 260 has not time to cause a closing of the circuit.

In order to stop the machine in the event that a thread should become wound around the tension-reducing means 100 or 101, I provide two feelers 263 (Figs. 23 and 36), one for each of said tension-reducing means.

Said feelers are fixed upon a rock shaft 264. A torsion spring 265 (Fig. 36) normally holds the feelers 263 in close proximity to the pins 103, the action of the spring being limited by contact of an arm 266 (Fig. 10)

fixed on the shaft 264 with a stop pin 267. In case a thread should become wound around the tension-reducing means 100 or 101, the thread will force the feelers 263 downwardly, thereby bringing the arm 266 into contact with an electrical contact 268, which contact is connected into the circuit of the electromagnet 251. When the members 266 and 268 are thus brought together, a circuit is closed through the electromagnet 251 and the machine promptly brought to a standstill.

When the machine is automatically stopped through winding of the reserve thread around the tension-reducing means 100, the slackening of the thread at the de-

tector 99 incident to such stopping would cause the knotter-actuating shaft 111 to be released. In order to prevent such release and thus prevent the running thread from being clamped and sheared at the knotter, I provide a hook 269 (Fig. 39) fixed to the belt-shifter 252, said hook being arranged to engage a pin 270 fixed on the shaft 137 and thereby rock the shaft 137 into position where the shoulder 136 can support the arm 134 of the knotter-actuating shaft 111.

When the machine is braked, the stoppage is, of course, not instantaneous. If the detector 99 (Fig. 23) were to act just before the belt-shifter 252 (Fig. 39) operated to shift the drive belt 82 to the loose pulley 84, the shoulder 64 (Fig. 11) might engage the dog 63 and begin to reset the mechanisms, but would not be able to complete the resetting operation before the machine came to a standstill. To prevent such partial resetting of the mechanisms while the machine is coming to a stop, I provide a lever 271 (Figs. 4 and 8) pivoted to the machine frame at 272 and having upon one side a block 273 (Fig. 12^b) that underlies a pin 274 fixed to the dog 63. The free end of the lever 271 rests at all times upon a pin 275 carried by a crank arm 276 fixed upon a rock shaft 277. Upon the other end of the shaft 277 is fixed a crank arm 278 which is connected by means of a link 279 (Fig. 12) with the arm 248. Thus when the arm 248 is released by the latch finger 249, the shaft 277 is rocked in the direction to lift the lever 271, the block 273 preventing the dog 63 from dropping into the path of movement of the shoulder 64 on the segment 65.

In case the machine should be automatically stopped through the action of the detector 260 or the feeler 263 for the tension-reducing means 101, it is necessary to rethread the machine. Before doing this the operator releases the arm 134 (Fig. 20) by pressing aside the arm 138, thereby causing the knotter to assume the position occupied after a tying operation. The thread is then drawn through the machine, and the machine started by means of the belt-shifter 252. The detent finger 200 (Fig. 8) is then manually disengaged from the finger 63^b, thus placing the resetting mechanism in operation to restore the knotter to normal position, index the magazine, and bring a new reserve thread into operative relation to the knotter.

It will be understood that the machine may be stopped by the operator at any time by manually unlatching the belt shifter 252.

In Figs. 1, 4, 8, 12 and 20 the machine is shown in normal running condition. When the bobbin that occupies the running position indicated in Fig. 31 is emptied or the thread breaks between the bobbin and the tension-reducing means, the detector fin-

130

gers 214 will no longer be supported by the thread and the shaft 137 will turn under the pressure of the arm 134, thus releasing said arm, whereupon the clamp members 119 and 124 (Figs. 17 and 18) are actuated to clamp the exhausted thread and the reserve thread, and the knotter is actuated to tie said threads together. At the same time the finger 185 (Fig. 4) disengages the thread from the 10 thread support 175, thus permitting winding to continue while the thread is clamped by the clamp member 124. The slack required as the threads are looped around the tying bill 107 is obtained through slippage 15 of the threads past the spring clamping finger 119 (Fig. 17). When the loops of the knot have been formed and the threads caught in the tying bill and there sheared and clamped, the stripper 131 pulls the loops 20 off the tying bill, tightens said loops and strips the clamped thread-ends out of the tying bill. Just before the shaft 111 comes to rest, the cam surface 123^a (Fig. 20), acting on the roller stud 122, causes the clamp 25 member 124 to be raised sufficiently to release the united threads. As the slack caused by the release of the united thread-ends is taken up in the winding operation, the thread straightens out and slips off the support 165, 30 passing down beside said support onto a shelf 280 and onto an inclined plate 281, said inclined plate assisting to guide the thread away from the hook 148. A guard finger 282 on the hook 148 also assists to 35 prevent the thread from being drawn across the top of said hook and eventually guides the thread to a plane below the hook.

When the arm 134 strikes and moves the stop 195, the resultant turning movement of 40 the shaft 197 opens the air valve and withdraws the detent finger 200 from the finger 63^b, thus allowing the spring 63^a to swing the dog 63 into the path of movement of the shoulder 64 on the segment 65. Upon the 45 next upward swing of said segment, the arms 60 and 62, the segment 174 and the cam 191 are moved, thereby turning the magazine to withdraw the exhausted bobbin from running position, swing inwardly the thread-guide 42 for the exhausted bobbin, and place 50 the bobbin which has been tied to the exhausted thread in running position, the yarn clearer also being opened for the reception of the running thread. The lever 55 170 also is swung upwardly to place the plate 171 above the plane of the thread. The thread support 175 also is moved into position alongside the thread guide 181; the pinion 188 (Figs. 13 and 15) is turned to 60 reset the knotter-actuating shaft 111; and the shaft 224 (Figs. 13 and 20) is turned to place the shaft 137 in position to hold the arm 134 in place. The arm 149 also is swung forwardly to place the hook 148 in the position shown in Figs. 5 and 6. As the arm 65

149 finishes its forward stroke, the air valve is closed, the waste ends having previously been withdrawn through the suction tube 116. As the lever 170 completes its upward movement, the projection 236 removes the stop 230 from beside the running thread, whereupon said thread quickly springs out of the tension-reducing means 100 and into the tension-reducing means 101, and consequently into position in front of the grid fingers 212 and beneath the uplifted plate 171. When the segment 65 swings downwardly, the plate 171 descends upon the running thread, thus forming a loop therein, the yarn clearer closes upon the running thread, the stop 230 is returned to normal position, the hook 148 draws the new reserve thread into proper position with reference to the knot tying mechanism, the thread support 175 moves rearwardly, thus carrying the thread away from the thread guide 181, and the pinion 188 and the shaft 224 return to normal position, the arm 134 being deposited on the shoulder 136. The pressure of the arm 134 against the shoulder 136 90 swings the detector fingers 214 against the running thread, the tension of the thread serving to hold the shoulder 136 in locking position.

As the running thread springs into engagement with the tension-reducing means 101, the thread leaves the shelf 280, drops onto the edge 114^a of the plate 114 and then slides into the throatways 115, 118, 128 and 130 (Fig. 17) and into place alongside the tying bill. The running thread enters the throatways just mentioned before the new reserve thread is moved into said throatways by the hook 148.

The operative removes empty bobbins from the magazine, replaces them with full bobbins and inserts the ends of the threads of the full bobbins in the clamps 26. The skewers are contracted as the empty bobbins are moved out of operative position, so that the empty bobbins may be readily lifted off and full bobbins dropped into place.

By reason of the high speed of winding, the thread balloons as it unwinds from the bobbin, thus enabling the yarn to unwind 115 freely.

While I have described the present embodiment of the invention in considerable detail, it should be understood that the invention is not limited to such details, but that on the contrary various changes may be made in the construction and relative arrangement of the various mechanisms without departing from the scope of the invention, as indicated by the appended claims.

I claim as my invention:

1. A winder having, in combination, a bobbin support, a thread guide above the bobbin support, tension-reducing means, a detector between the thread guide and the

- 5 tension-reducing means, a knotter, loop-forming means between the tension-reducing means and the knotter, winding means, means for releasably holding the thread at a point between the knotter and the winding means, a reserve bobbin support, a clamp for the end of the thread on the reserve bobbin, means for moving the reserve thread into proximity to the knotter, detector-controlled means for moving the reserve thread into the knotter and for actuating the knotter, and detector-controlled means for releasing the thread from said holding means.
- 10 2. A winder having, in combination, a bobbin support, tension-reducing means, a detector between the thread guide and the tension-reducing means, a knotter, loop-forming means between the tension-reducing means and the knotter, winding means, means for releasably holding the thread at a point between the knotter and the winding means, a reserve bobbin support, means for supporting a reserve thread in proximity to the knotter, and detector-controlled means for moving the reserve thread into the knotter and for actuating the knotter.
- 15 3. A winder having, in combination, a bobbin support, tension-reducing means, a detector between the bobbin support and the tension-reducing means, a knotter, a spring for actuating the knotter, winding means, a reserve bobbin support, means for supporting a reserve thread in proximity to the knotter, and detector-controlled means for moving the reserve thread into the knotter and for releasing the knotter to actuation.
- 20 4. A winder having, in combination, a bobbin support, a knotter, a detector between the bobbin support and the knotter, winding means, means for releasably holding the thread at a point between the knotter and the winding means, means for supporting a reserve thread in proximity to the knotter, a spring for actuating the knotter to tie a knot, detector-controlled means for moving the reserve thread into the knotter and for releasing the knotter to actuation, and means to reset the knotter.
- 25 5. A winder having, in combination, a bobbin support, a knotter, a detector between the bobbin support and the knotter, winding means, means for supporting a reserve thread, a spring for actuating the knotter to unite the exhausted thread and the reserve thread, detector-controlled means for releasing the knotter to the action of said spring, and means automatically to reset the knotter.
- 30 6. A winder having, in combination, means for holding an active and a reserve thread supply; means for holding the end of the reserve thread; means for continuously rotating a winding carrier upon which the active thread is wound; a normally idle knotter
- 35 7. A winder having, in combination, a knotter comprising an angular tying bill, means for winding a thread extending within the angle of the bill, means to support a reserve thread adjacent to the bill, means for moving the reserve thread laterally into place within the angle of the bill, a spring to actuate the reserve-thread-moving means and the knotter, thread-controlled means to restrain the spring, and means for resetting the knotter and said reserve-thread-moving means.
- 40 8. A winder having in combination, a support for an active thread supply, a support for a reserve thread, continuously-operating winding means, a knotter for uniting said threads, means for normally holding the active thread in the form of a loop between the winding means and the knotter, and means for releasing the active thread from said holding means upon actuation of the knotter.
- 45 9. A winder having, in combination, a support for an active thread supply, winding means, means for tying a reserve thread to the active thread upon exhaustion of the latter, a guide for supporting the active thread to run in an indirect path between the tying means and the winding means, and means to disengage the active thread from said guide upon exhaustion of the thread to furnish thread to the winding means.
- 50 10. A winder having, in combination, a support for an active thread supply, winding means, means for tying a reserve thread to the active thread upon exhaustion of the latter, a guide for supporting the thread to run in an indirect path between the tying means and the winding means, means to disengage the active thread from said guide upon the exhaustion of the latter, to furnish thread to the winding means, said guide being movable into thread-retrieving position and back to normal position, and means for thus moving said guide.
- 55 11. A winder having, in combination, a guide for the thread being wound, an auxiliary thread guide, a device to disengage the thread being wound from the first mentioned thread guide, said first mentioned thread guide being movable into position adjacent to the auxiliary thread guide to receive the thread from said auxiliary thread guide, and means for operating the first mentioned thread guide.
- 60 12. A winder having, in combination, a

- support for an active thread supply, winding means, a knotter, a device to clamp the active thread, when exhausted, adjacent to the knotter, a guide for supporting the thread to run in an indirect path between the knotter and the winding means, and means to disengage the thread from said guide when the thread is clamped at the knotter.
10. 13. A winder having, in combination, a support for an active thread supply, winding means, a knotter, a device to clamp the thread when exhausted at the knotter, a guide for supporting the thread to run in an indirect path between the knotter and the winding means, an auxiliary thread guide near the knotter, a device to disengage the thread from the first mentioned thread guide when the thread is clamped at the knotter to allow the thread to move into engagement with the auxiliary thread guide, and means for moving the first mentioned thread guide to take the thread from the auxiliary guide and return it to its normal position.
14. A winder having, in combination, a support for an active thread supply, winding means, a knotter past which the active thread runs, a guide for supporting the thread to run in an indirect path between the knotter and the winding means, and means to disengage the thread from said guide.
15. A winder having, in combination, a support for an active thread supply, winding means, a knotter past which the active thread runs, a detector to detect exhaustion of the active thread, said detector controlling the knotter, a guide for supporting the thread to run in an indirect path between the knotter and the winding means, and means controlled by the detector for disengaging the thread from said guide upon exhaustion of the thread.
16. A winder having, in combination, a support for an active thread supply, winding means, a stationary knotter adjacent to which the active thread runs, means for normally holding the thread in the form of a loop between the winding means and the knotter and means for releasing the thread from said holding means when the knotter is actuated.
17. A winder having, in combination, a support for a reserve thread mass, a knotter, means for supporting a loop of the reserve thread in proximity to the knotter, a tension reducer near the loop, a member to hold one strand of the loop out of engagement with the tension reducer, and means for moving said member into and out of operative position.
18. A winder having, in combination, a support for a reserve thread mass, a knotter, means for supporting the thread of said mass in proximity to the knotter, a tension reducer near the thread, a member to hold the thread out of engagement with the tension reducer, and means for moving said member into and out of operative position.
19. A winder having, in combination, a support for a thread mass, a device to hold the end of the thread of the mass, a knotter, a hook arranged to engage the thread at a point between the thread mass and said holding device, means for moving said hook to draw a loop of the thread into proximity to the knotter and for swinging the hook to clear the knotter, a tension reducer at one side of the loop, a member to hold one strand of the loop out of engagement with said tension reducer, and means for moving said member into and out of operative position.
20. A winder having, in combination, a support for a thread carrier, a device to hold the end of the thread on the thread carrier, a knotter, a tension reducer, two stop members adjacent to said tension reducer, a hook arranged to engage the thread at a point between said stop members to draw a loop of the thread into proximity to the knotter, and means for moving said stop members out of engagement with the thread to permit one strand of the loop to engage the tension reducer and to cause slack in the other strand of the loop.
21. A winder having, in combination, a support for a reserve thread mass, a stationary knotter having an angular tying bill, means to support the thread of said reserve thread mass in proximity to the knotter, a support for an active thread mass, means for winding the active thread, the latter running within the angle of the tying bill, and automatically-operating means for actuating the knotter to unite the active and the reserve thread upon exhaustion of the former.
22. A winder having, in combination, a stationary knotter, a reserve thread support, a device to draw the reserve thread into the form of a loop, the loop being in proximity to the knotter, and a device to move one strand of said loop into the knotter.
23. A winder having, in combination, a magazine for supporting a plurality of thread carriers, two tension reducers, means for moving the magazine to transfer the thread carriers from operative relation to one tension reducer and into operative relation to the other tension reducer, and a stop movable into and out of position to delay the movement of successive threads out of engagement with the first tension reducer.
24. A winder having, in combination, a magazine for supporting a plurality of thread carriers, two tension reducers, means for moving the magazine to transfer the thread carriers from operative relation to

- one tension reducer and into operative relation to the other tension reducer, and means to delay the movement of successive threads out of engagement with the first tension reducer.
25. A winder having, in combination, a support for a reserve thread carrier, a support for an active thread carrier, winding means, means for moving said supports to place the reserve thread carrier in the position previously occupied by the active thread carrier, a tension reducer arranged to act upon the thread while being drawn from the reserve thread carrier, and a tension reducer to act upon the thread when the reserve thread carrier is advanced into active position, and a stop movable into and out of position to delay the movement of the thread out of engagement with the first tension reducer.
- 13 26. A winder having, in combination, a rotatable magazine comprising a series of skewers each for supporting a thread carrier, a series of thread guides on the magazine, there being one thread guide for each skewer, and means for moving the thread guides toward and away from axial relation to the skewers.
- 25 27. A winder having, in combination, a rotatable magazine comprising a series of thread-carrier supports, a series of thread guides on the magazine there being one thread guide for each thread-carrier support, and means for moving the thread guides into 35 and out of operative relation to the thread-carrier supports.
28. A winder having, in combination, a magazine comprising a series of skewers each for supporting a thread carrier, a series of devices to hold the ends of the threads on said thread carriers, a device at one side of the path of movement of the thread carriers for guiding the thread, and a series of co-operating thread guides on the magazine, 40 there being one of the last mentioned thread guides for each skewer, and means for moving the last mentioned thread guides to place the threads in operative relation to the first mentioned thread-guiding means.
- 45 50 29. A winder having, in combination, a support for a reserve-supply thread mass, a support for the end of the thread of said mass, a knotter, and a hook reciprocable to engage the thread between the thread mass and said holding device and draw a loop of the thread into proximity to the knotter, said hook being normally stationary in loop-supporting position.
- 55 60 30. A winder having, in combination, a stationary knotter, a series of reserve thread-mass supports, a reciprocatory hook for drawing a loop of a reserve thread into proximity to the knotter, and means for intermittently moving the series of thread masses to bring the threads successively within reach of the hook.
31. A winder having, in combination, a stationary knotter, a rotatable thread-mass magazine, a hook for moving a thread of one of the thread-masses into proximity to the knotter, and means for turning the magazine to bring successive threads within reach of the hook.
32. A winder having, in combination, a stationary knotter, a series of bobbin supports, a series of clamps for the threads of the bobbins, a reciprocable member for moving a thread into proximity to the knotter, and means for intermittently moving said bobbin supports and clamps to bring threads successively within reach of said member.
- 75 33. A winder having, in combination, a stationary knotter, a magazine for supporting thread carriers, a series of devices moving with the magazine for holding the ends of the threads on the thread carriers, a device for engaging a thread between its carrier and the corresponding thread-holding device and drawing the thread into the form of a loop and moving the loop into proximity to the knotter, and means for moving the magazine and said series of holding devices to carry the threads successively into operative relation to the thread-engaging device.
- 85 90 95 34. A winder having, in combination, a rotatable magazine for supporting thread carriers, means rotating with, and on the same axis as, the magazine for holding the ends of the threads on the thread carriers, a device for taking one of the threads and drawing it into the form of a loop, and means for turning the magazine and said thread-holding means to carry the threads laterally into operative relation to the thread-taking device.
- 100 105 110 115 35. A winder having, in combination, a support for an active thread supply, a detector to detect exhaustion of the active thread, continuously-operating winding means, a knotter stationarily located between the detector and the winding means and controlled by the detector, and means for forming a loop in the thread between the detector and the knotter, so that the free end of the exhausted thread shall not pass the knotter before the latter acts.
- 120 125 36. A winder having, in combination, a support for an active thread supply, a support for a reserve thread, winding means, a knotter for automatically uniting said threads upon exhaustion of the active thread, and means for normally maintaining a loop in the active thread between the thread supply and the knotter, said means including an arm arranged to swing in one direction to a position above the reserve thread, said arm having at its free end a

notched member to engage the reserve thread after the latter has been tied to the exhausted thread, the swinging movement of said arm in the opposite direction serving to draw a 5 loop in the thread.

37. A winder having, in combination, winding means, a skewer for the bobbin being rewound, a device for drawing a loop in the thread, said device being movable into 10 position above the horizontal plane of the thread, means for moving the skewer to move the bobbin laterally, a stop to prevent the thread from moving laterally into place beneath said device under the tension of 15 winding, and means for withdrawing said stop.

38. A winder having, in combination, winding means, a skewer for the bobbin being rewound, a device for drawing a loop in 20 the thread, said device being movable into position above the horizontal plane of the thread, means for moving the skewer to move the bobbin laterally, and means to control the lateral movement of the thread into 25 place beneath said device under the tension of winding.

39. A winder having, in combination, a magazine having a plurality of individual compartments for supply bobbins, the outer 30 sides of said compartments being open for the removal and insertion of bobbins, and stationary means for closing the outer side of a compartment in the rotation of the magazine.

40. A winder having, in combination, a rotatable magazine having a plurality of individual compartments for supply bobbins, the outer sides of said compartments being open 35 for the removal and insertion of bobbins, stationary means for closing the outer side of a compartment, a stationary thread guide for such closed compartment, thread guides carried by the magazine and corresponding in number to the number of compartments, 40 the last mentioned thread guides being movable into and out of operative relation to the stationary thread guide in the rotation of the magazine, and rotatable means above the thread guides for holding the ends of 45 threads of bobbins in said compartments.

41. A winder having, in combination, a rotatable series of expandable skewers, means for operating said skewers to clamp and release supply bobbins, and rotatable means 50 for clamping the ends of the threads of the bobbins.

42. A winder having, in combination, means for winding a thread, means for tying a reserve thread onto the thread being 55 wound, said tying means including an arm, a spring tending to swing said arm, and means including a part adapted to bear upon the running thread for obstructing the swinging movement of said arm.

43. A winder having, in combination, a 65 rotatable spindle, an annular series of supply-bobbin skewers surrounding and carried by the spindle, said skewers extending approximately longitudinally of the spindle, and means carried by the spindle for holding the ends of the threads of bobbins mounted on said skewers. 70

44. A winder having, in combination, a rotatable series of supply-bobbin skewers extending approximately parallel with each 75 other, and rotatable means for holding the ends of the threads of supply bobbins mounted on said skewers.

45. A winder having, in combination, a rotatable spindle, an annular series of expandable skewers carried by the spindle, means for operating said skewers to clamp and release supply bobbins, and rotatable means approximately aligned with the skewers for holding the ends of the threads of the 85 bobbins. 80

46. A winder having, in combination, a movable series of individual compartments for supply bobbins, one side of each compartment being open for the removal and 90 insertion of bobbins, and means for closing said side of the compartment when the compartment reaches a certain point.

47. A winder having, in combination, a movable series of individual compartments 95 for supply bobbins, a vertical skewer in each compartment for supporting the supply bobbin, one side of each compartment being open for the insertion and removal of bobbins, and means for closing said side of the 100 compartment in the movement of the series of compartments.

48. A winder having, in combination, a rotatable magazine having a plurality of compartments, a supply-bobbin skewer in 105 each compartment, the outer sides of said compartments being open for the removal and insertion of bobbins, and stationary means for closing the outer side of a compartment in the rotation of a magazine. 110

49. A winder having, in combination, a rotatable magazine having a plurality of compartments, a supply-bobbin skewer in each compartment, the outer sides of said compartments being open, stationary means for closing the outer side of a compartment in the rotation of the magazine, thread-guiding means for the thread of the bobbin in such closed compartment, and means rotating with the magazine above the plane of 115 said thread-guiding means for holding the ends of the threads of the bobbins. 120

50. A winder having, in combination, a support for a reserve thread carrier, a support for an active thread carrier, winding means, means for moving said supports to place the reserve thread carrier in the position previously occupied by the active thread 125

- carrier, a tension reducer arranged to act upon the thread while being drawn from the reserve thread carrier, and a tension reducer to act upon the thread when the reserve thread carrier is advanced into active position.
51. A winder having, in combination, winding means, a tension reducer, a rotatable magazine comprising a series of bobbin supports and a series of clamps for the threads of the bobbins, and means for rotating the magazine step by step to position successive threads in proximity to the tension reducer.
52. The combination of a rotatable bobbin-creeel, clamps rotating with the creel to hold the ends of the threads of the bobbins, and means to open the clamps.
53. The combination of a rotatable bobbin-creeel, clamps rotating with the creel to hold the ends of the threads of the bobbins, and means to open the clamps in succession as they reach a certain point in their orbit.
54. A winder having, in combination, a traveling series of supports for thread carriers, and a yarn clearer into which the threads are successively carried in the travel of the series.
55. A winder having, in combination, a rotatable magazine for supporting thread carriers before, during and after unwinding, and a yarn clearer into which the threads are successively carried in the rotation of the magazine.
56. A winder having, in combination, a rotatable magazine for supporting thread carriers, a yarn clearer into which the threads are successively carried in the rotation of the magazine, and means for rotating the magazine and opening and closing the yarn clearer.
57. A winder having, in combination, means for winding a thread, a circular series of staggered elements engaging the thread being wound, means for guiding the thread to describe an arc in passing said series, and means for rotating the series at greater peripheral speed than the speed of winding.
58. A winder having, in combination, means for winding a thread, a roll having a greater peripheral speed than the speed of winding, means for guiding the running thread to describe an arc in passing said roll, and means within the roll to produce other arcs of contact with the thread, said roll being peripherally grooved to enable the thread to move into and out of contact with said interior means.
59. A winder having, in combination, means for winding a thread, a travelling endless series of staggered elements engaging the thread being wound, and means for moving said series at a greater speed than the speed of winding.
60. A winder having, in combination,
- means for winding a thread, a wheel having a peripheral series of staggered pins engaging the thread being wound, and means for guiding the thread to describe an arc in passing the wheel, said pins projecting away from the axis of the wheel, said wheel having greater peripheral speed than the speed of winding.
61. A winder having, in combination, means for winding a thread, a roll having a greater peripheral speed than the speed of winding, and a series of staggered elements within the roll and rotating therewith, said roll being peripherally grooved to enable the thread to move into and out of contact with said elements, and means for guiding the running thread to describe an arc in passing said roll.
62. A winder having, in combination, a support for a supply thread mass, means for unwinding thread from said thread mass, and means for equalizing the tension of the thread in the region between the equalizing means and the winding means.
63. A winder having, in combination, a magazine comprising a series of non-rotatable supply-bobbin skewers, each skewer being operable to clamp and release a bobbin, means for moving the series of skewers, and means for operating the skewers.
64. A winder having, in combination, a rotatable magazine comprising a series of non-rotatable supply-bobbin skewers, each skewer being operable to clamp and release a bobbin, means for rotating the magazine, and means for operating the skewers.
65. A winder having, in combination, a rotatable magazine comprising a series of non-rotatable supply-bobbin skewers, each skewer being operable to clamp and release a bobbin, means for rotating the magazine, a stationary cam member, and a device associated with each skewer and arranged to be carried into engagement with said cam member in the rotation of the magazine for operating the skewers.
66. A winder having, in combination, a rotatable magazine comprising a series of devices each arranged to clamp one end of a supply bobbin, means for rotating the magazine, and means for operating said clamping devices to clamp and release bobbins.
67. A winder having, in combination, a rotatable magazine comprising a series of non-rotatable devices each arranged to clamp one end of a supply bobbin, means for turning the magazine step by step, means for operating said clamping devices to clamp bobbins, and means for successively operating the clamping devices to release the bobbins.
68. A winder having, in combination, a rotatable magazine having a plurality of bobbin supports, a stationary thread guide,

- and thread guides rotating with the magazine and corresponding in number to the number of bobbin supports, the last mentioned thread guides being movable into and 5 out of operative relation to the stationary thread guide in the rotation of the magazine.
69. A winder having, in combination, a rotatable magazine having a plurality of bobbin supports, a stationary thread guide, 10 thread guides rotating with the magazine and corresponding in number to the number of bobbin supports, the last mentioned thread guides being movable into and out of operative relation to the stationary thread guide 15 in the rotation of the magazine, and means above the thread guides for holding the ends of threads of bobbins on said supports.
70. A winder having, in combination, a rotatable magazine, a series of thread guides 20 rotating with the magazine, and a stationary thread guide, the first mentioned thread guides being arranged to coat successively with the stationary guide in the rotation of the magazine and being movable in and out 25 with respect to the magazine as the latter turns.
71. A winder having, in combination, a support for a bobbin, a device to hold the end of the thread on the bobbin, thread-guiding means, and means for moving the 30 bobbin support and the thread-holding device to carry the thread into operative relation to the thread-guiding means.
72. A winder having, in combination, a support for a bobbin, a device to hold the end of the thread on the bobbin, thread-guiding means including a stationary member and a coacting member movable away from the stationary member to receive a thread, and 35 means for moving the bobbin support and the thread-holding device to carry the thread into operative relation to the stationary thread-guiding member.
73. A winder having, in combination, a rotatable series of thread guides and a stationary thread guide, the first mentioned 40 thread guides being arranged to coat successively with the stationary guide at one point in their orbit.
74. A skewer for supporting a thread carrier having, in combination, a plurality of longitudinal segments, a stationary conical member engaging the lower ends of said segments, a pin extending axially of said segments, the upper end of said pin having a 45 conical surface adapted to enter between the segments, means tending to move the segments toward each other, and means for longitudinally moving the pin to move the said 50 conical surface toward the conical member.
75. A winder having, in combination, a rotatable series of thread guides and a stationary thread guide, the first mentioned 55 thread guides being arranged to coat successively with the stationary guide at one point in their orbit; and being reciprocable in the rotation of the series into and out of operative position.
76. A thread-carrier support consisting of a skewer having an expansible lower end, a 60 stationary conical member fitting into the lower end of the skewer, said skewer being longitudinally movable with relation to said conical member, and means for moving the skewer longitudinally toward the larger portion of the conical member.
77. A winder having, in combination, a rotatable series of thread guides, and a stationary thread guide, the first mentioned 65 thread guides being movable into and out of operative relation to the stationary guide.
78. A winder having, in combination, a rotatable series of supply-bobbin skewers extending approximately parallel with each other, a series of thread guides corresponding 70 in number to the skewers, and a stationary thread guide, the first mentioned thread guides being movable in the rotation of the series of skewers into and out of operative relation to the stationary guide.
79. A winder having, in combination, a rotatable spindle, an annular series of supply-bobbin skewers surrounding and carried by the spindle, the skewers extending approximately longitudinally of the spindle, 75 a series of thread guides corresponding in number to the skewers, said thread guides being carried by the spindle, a stationary thread guide, the first-mentioned thread guides being movable in the rotation of the spindle into and out of operative relation to the threads of the bobbins on the skewers and to said stationary guide, and means on the spindle above said thread guides for holding the ends of said threads.
80. A winder having, in combination, a rotatable series of supply-bobbin skewers, the skewers extending approximately parallel with each other, a series of thread guides corresponding in number to the skewers, said 80 series of thread guides being rotatable with the series of skewers, said series of thread guides being movable in the rotation of said series into and out of operative relation to the threads of the bobbins on the skewers, and rotatable means above said thread guides for holding the ends of said threads.
81. A winder having, in combination, winding means, a support for a bobbin, a guide for the thread of the bobbin, a detector between the guide and the bobbin, means for moving the bobbin support in the direction to carry the thread laterally toward the detector, a stop adjacent to the guide to prevent the thread from moving laterally into operative relation to the detector under the tension of winding, and means for withdrawing said stop.
82. A winder having, in combination, winding means, a skewer for a bobbin, a de- 130

5 tector located above and at one side of the bobbin, means to move the skewer to carry the bobbin laterally toward the detector, and means to control the lateral movement of the 10 thread into operative relation to the detector under the tension of winding.

83. A winder having, in combination, winding means, a support for a bobbin, a detector, means for causing movement of the 10 bobbin in the direction to carry the thread laterally toward the detector, and means to control lateral movement of the thread into operative relation to the detector under the tension of winding.

15 84. A winder having, in combination, winding means, a support for a bobbin, two tension-reducers for the thread of the bobbin, means for moving the bobbin support to move the bobbin laterally toward one of 20 the tension-reducers, a stop adjacent to the other tension-reducer to prevent the thread from moving laterally under the tension of winding, and means for withdrawing said stop.

25 85. A winder having, in combination, means for winding the thread of a bobbin, a tension-reducer, means for moving the bobbin to carry the thread laterally toward the tension-reducer, a stop to prevent the 30 thread from moving laterally into operative relation to the tension-reducer under the tension of winding, and means for withdrawing said stop.

35 86. A winder having, in combination, means for winding the thread of a bobbin, a tension-reducer, means for moving the bobbin to carry the thread laterally toward the tension-reducer, and means to control the movement of the thread into operative 40 relation to the tension-reducer under the tension of winding.

45 87. A winder having, in combination, winding means, a support for a bobbin, a detector, means for causing movement of the bobbin in the direction to carry the thread laterally toward the detector, a stop to prevent the thread from moving laterally into operative relation to the detector under the tension of winding, and means for 50 withdrawing said stop.

55 88. A winder having, in combination, winding means, a support for a bobbin, two tension-reducers for the thread of the bobbin, a detector adjacent to one of the tension-reducers, means for moving the bobbin support in the direction to carry the thread laterally toward the detector, a stop adjacent to the other tension-reducer to prevent the thread from moving laterally into operative relation to the detector and the adjacent tension-reducer under the tension of winding, and means for withdrawing said 60 stop.

65 89. A winder having, in combination, winding means, a support for the bobbin

being rewound, two tension-reducers to reduce the tension of the thread of the bobbin, and means for causing movement of the bobbin out of operative relation to one tension-reducer and into operative relation to the other.

70 90. A winder having, in combination, winding means, a skewer for a bobbin, a tension-reducer above and at one side of the bobbin, and means for moving the skewer to carry the bobbin laterally into operative relation to the tension-reducer.

75 91. A winder having, in combination, means for rewinding the thread of a thread carrier, a tension reducer to reduce the tension of said thread, means to move the thread carrier to another position, and a tension reducer to act upon the thread after the thread carrier has been thus moved.

80 92. A winder having, in combination, winding means, a tension reducer, a series of bobbin supports, a series of clamps for the threads of the bobbins, and means for moving said two series to position successive threads in proximity to the tension 90 reducer.

85 93. A winder having, in combination, winding means, a skewer for a bobbin, a detector above and at one side of the bobbin, and means for moving the skewer to carry the bobbin laterally toward the vertical plane of the detector.

90 94. A winder having, in combination, winding means, a skewer for a bobbin, a detector, and means for moving the skewer 100 in the direction to carry the thread laterally to the detector and place the bobbin in approximately axial alinement with the detector.

95 95. A winder having, in combination, 105 a skewer for supporting a supply bobbin, thread-guiding means, and means for moving the skewer to carry the bobbin laterally into axial alinement with the thread-guiding means.

110 96. A winder having, in combination, a skewer for supporting a supply bobbin, thread-guiding means, and means for moving the skewer to carry the bobbin laterally into operative relation to the thread-guiding means.

115 97. A winder having, in combination, a skewer for supporting a supply bobbin, thread-guiding means, and means for moving the skewer to carry the bobbin laterally into place beneath the thread-guiding means.

120 98. A winder having, in combination, a knotter, a spring for actuating the knotter, thread-controlled means to restrain the spring, and means rendered effective by the operation of the knotter for resetting the knotter.

125 99. A winder having, in combination, a knotter, a spring to actuate the knotter,

thread-controlled means to restrain the spring, means to reset the knotter, an actuator for the resetting means, and means controlled by the knotter for connecting the resetting means to the actuator.

100. A winder having, in combination, a knotter, a tension reducer, a partition extending from a point above the knotter to a point close to the tension reducer, a pivoted arm, a hook pivoted to said arm, said arm being arranged to swing rearwardly to carry the hook from the tension reducer to the knotter and thus draw a loop of thread to the knotter with the two strands of the loop at opposite sides of said partition, means to cause said hook to swing downwardly adjacent to the knotter as said arm completes its rearward swing to place one of said strands in position adjacent to the knotter, and a thread support upon which the other strand is laid as the hook swings downwardly into position adjacent to the knotter.

101. A winder having, in combination, a knotter, means to support a reserve thread, a partition extending from a point above the knotter to a point close to the reserve thread, a hook arranged to engage the reserve thread and draw a loop thereof to the knotter with the two strands of the loop at opposite sides of said partition, means to cause said hook to swing downwardly adjacent to the knotter to place one of said strands in position adjacent to the knotter, and a thread support upon which the other strand is laid as the hook swings downwardly.

102. A winder having, in combination, a knotter, means to support a reserve thread, a hook arranged to engage said thread and draw a loop thereof to the knotter, means to cause said hook to swing downwardly adjacent to the knotter to place one of said strands in position adjacent to the knotter, and a thread support upon which the other strand is laid as the hook swings downwardly.

103. A winder having, in combination, a knotter, means to wind a thread extending adjacent to the knotter, means to support a reserve thread, a hook arranged to engage said reserve thread and draw a loop thereof to the knotter and support one strand of the loop alongside the thread being wound, and means to place said strand and the thread being wound in the knotter.

104. A winder having, in combination, a knotter comprising an angular tying bill, means for winding a thread extending within the angle of the bill, means to support a reserve thread alongside the other thread, a clamping arm at one side of the tying bill to push the reserve thread into place alongside the other thread and clamp said threads, an arm pivoted at the other side of the tying bill to clamp said threads, and a stripper ar-

ranged to engage the united threads to tighten and strip the knot.

105. A winder having, in combination, a knotter comprising an angular tying bill, means for winding a thread extending within the angle of the bill, means to support a reserve thread alongside the other thread, a clamping arm at one side of the tying bill to push the reserve thread into place alongside the other thread and clamp said threads, an arm pivoted at the other side of the tying bill, a clamp into which the last mentioned arm is arranged to force the threads, and a pivoted stripper arm arranged to engage the threads at a point between said clamp and the tying bill to tighten and strip the knot.

106. A winder having, in combination, a knotter comprising an angular tying bill, means for winding a thread extending within the angle of the bill, means to support a reserve thread alongside the other thread, a suction tube at the side of the tying bill from which the first mentioned thread approaches, a clamping arm between the suction tube and the tying bill to push the reserve thread into place alongside the other thread and clamp said threads, an arm pivoted at the other side of the tying bill, a clamp into which the last mentioned arm is arranged to force the threads, and a pivoted stripper arm arranged to engage the threads at a point between said clamp and the tying bill to tighten and strip the knot.

107. A winder having, in combination, a knotter comprising an angular tying bill, means for winding a thread extending within the angle of the bill, means to support a reserve thread alongside the other thread, a suction tube at the side of the tying bill from which the first mentioned thread approaches, a spring clamping arm between the suction tube and the tying bill to push the reserve thread into place alongside the other thread and clamp said threads, an arm pivoted at the other side of the tying bill, a spring clamp into which the last mentioned arm is arranged to force the threads, said arms being connected together to rotate upon a common axis, the first mentioned arm being arranged to clamp the threads before the tying bill engages said threads to form the loops of the knot, and a pivoted stripper arm arranged to engage the threads at a point between said spring clamp and the tying bill to tighten and strip the knot.

108. A winder having, in combination, a tension-reducer to reduce tension in the thread being wound, means to stop the winder, and a feeler controlling said stopping means and sensitive to the winding of thread around the tension-reducer.

109. A winder having, in combination, a tension-reducer to reduce tension in the thread being wound, a detector for the thread being wound, a knotter normally con-

trolled by the detector, means to stop the winder, a feeler controlling the stopping means and sensitive to the winding of thread around the tension-reducer, and means to 5 take control of the knotter away from the detector upon stoppage of the winder.

110. A winder having, in combination, a knotter, a detector normally controlling the knotter, means to stop the winder, and 10 means to take control of the knotter away

from the detector upon stoppage of the winder.

111. A winder having, in combination, a knotter, resetting means, means to stop the winder, and means controlled by the stop- 15 ping means to disable the resetting means.

In testimony whereof I have hereunto set my hand.

HOWARD D. COLMAN.
